UNITED STATES PATENT OFFICE

103,252

DESIGN FOR A COMBINED TICKET MUTILATING AND COMMODITY DISPLAY CABINET

Ernest V. Richards, Jr., New Orleans, La.

Application December 7, 1936, Serial No. 66,375

Term of patent 14 years

To all whom it may concern:

Be it known that I, Ernest V. Richards, Jr., a citizen of the United States, residing at New Orleans, in the Parish of Orleans, and State of Louisiana, have invented a new, original, and ornamental Design for a Combined Ticket Mutilating and Commodity Display Cabinet, of which the following is a specification, reference being had to the accompanying drawings, forming a part thereof.

Figure 1 is a front elevational view of the combined mutilating and commodity display cabinet, showing my design;

Figure 2 is a side elevational view;

Figure 3 is a top plan view;

Figure 4 is a side elevational view of the side of the cabinet opposite to the side shown in Fig. 2; and

Figure 5 is a rear elevational view of the cabinet.

I claim:

The ornamental design for a combined ticket mutilating and commodity display cabinet, as shown.

ERNEST V. RICHARDS, JR.
